PATIENT STATUS INDICATOR

Mildred Jaynes, Amherst Junction, Wis. 54467

Filed Dec. 12, 1975, Ser. No. 640,282

Term of patent 14 years

Int. Cl. D28—03

U.S. Cl. D96—12 R

FIG. 1 is an exploded perspective view of a patient status indicator showing my new design with the indicator module shown removed from the receptacle which is designed for wall or door mounting;

FIG. 2 is a front plan view of the embodiment of FIG. 1 with the indicator module in place showing the ambulatory position;

FIG. 3 is a top view of the indicator of FIG. 2;

FIG. 4 is a side view of the indicator of FIG. 2; and

FIG. 5 is a bottom view of the indicator of FIG. 2.

The ambulatory portion of the indicator module is lined to indicate green, the wheelchair indicator portion of the module is lined to indicate yellow, and the bed patient portion of the indicator module is lined to indicate red.

The back of the patient status indicator is plain and unornamented.

I claim:

The ornamental design for a patient status indicator, substantially as shown and described.
